UNITED STATES PATENT OFFICE.

LUCIEN CHARLES EILERTSEN, OF PARIS, FRANCE.

RHEOSTAT.

1,019,616.

Specification of Letters Patent.

Patented Mar. 5, 1912.

Application filed March 28, 1911. Serial No. 617,468.

To all whom it may concern:

Be it known that I, LUCIEN CHARLES EILERTSEN, a citizen of the French Republic, and resident of Paris, France, have invented a certain new and useful Rheostat, of which the following is a specification.

This invention relates to a new rheostat adapted to be controlled from a distance.

In the accompanying drawings, given by way of example: Figure 1 shows diagrammatically one form of embodiment of a rheostat constructed according to the principles of the present invention; Fig. 2 shows in a similar manner a modified form based on the same principle. Fig. 3 shows a vertical section of an actuating device.

In the form of embodiment shown by Fig. 1, the rheostat comprises two vessels A and B having preferably a tubular shape communicating through tube 3 and filled with mercury up to a determined level *h*. Arranged around the vessel A and passing through the wall of this vessel is a series of conducting wires C which are insulated 25 from each other and the inner ends D of which are free inside the vessel A while the other ends D' are soldered at intervals to a long wire R which is wound in the shape of a helix or arranged in any other manner so 30 as to form a resistance through which the current to be controlled passes. The receptacle B is provided with a tubular extension T and is closed at its upper part. A tube F communicating with a receptacle G descends 35 into the vessel B, the receptacle G containing mercury so as to maintain the level of fluid in a constant manner at *h* and to compensate the loss of mercury which might occur by evaporation or owing to any other 40 cause. The tube A may receive above the mercury a layer of a non-conducting liquid H intended to protect the mercury and the ends of the conducting wires from any alteration.

45 The tubular extension T communicates with a small apparatus which is intended to produce the variations of pressure which cause the variations of the mercury level. This apparatus may be stationary or be held 50 in the hand and be constructed in the following manner: Arranged at the upper end of a holder X is a tube *k* provided with a cock L and communicating at one end by means of a flexible tube N with any suitable 55 source of compressed air and at the other end with two flexible tubes *o* and *o'* the first one connects it with the tubular extension T and the other with a small apparatus which serves to indicate the level of the mercury in the rheostat and consequently the intensity of the current. A third rigid tube O' 60 provided with a cock L' serves to regulate the escape. The controlling apparatus showing the level of the mercury in the rheostat is also formed of two tubes, 1 and 2 communicating with each other and filled with mercury up to a determined level; the said two tubes are engaged into each other so that the inner tube 1 plays the part of a bell in which the mercury descends while it 65 rises in the outer tube 2. The bell 1 communicates with the tube *k* through the medium of the tube O' and is subjected to the same variations of pressure as the rheostat 70 proper.

75 This apparatus may be suspended from the ceiling and be raised and lowered by means of a pulley; it may also be rendered movable by any other means but in such a manner that it is always positioned in front 80 of the eyes of the operator.

The working of the device will be readily understood from the foregoing specification. The level of the mercury being the same in both vessels A and B the current passes 85 through the entire resistance R; if it is desired to put the latter out of the circuit all that will be necessary is to increase the air pressure by opening the cock L, the more this pressure increases the higher the level 90 of the mercury rises in the vessel A and correspondingly descends in the vessel B; in proportion to the increase of the pressure the mercury will come into contact with a larger number of conductors *l* thus canceling a corresponding proportion of the 95 resistance R. For reducing the pressure the cock L' is opened; the mercury level therefore will descend so that the resistance is increased; as readily seen this resistance 100 is controlled by simply varying the pressure and consequently the level. The same fluctuations of the level will be reproduced on the indicating apparatus thereby allowing 105 of the working of the rheostat to be accurately controlled. The current may also be caused to flow between the end E of the resistance and a conductor V dipping at all times direct into the mercury, the results obtained will be the same. In practice, as 110 it is useful to be able to perform by means of a single finger the two maneuvers neces-

sary for the working of the apparatus, the arrangement shown by Fig. 3 may be adapted. Here the two cocks L and L' are replaced by two valves S and S' which alternately open and close two ports P and P'. The port P establishes the communication between the chamber α and the chamber α' while port P' establishes the communication between the chamber α' and the atmosphere.

10 The chamber α receives compressed air from the tubular extension T is closed by a piston and a third valve S'' which is held in a closed position by a spring in such a manner that by pushing on a button U by 15 means of a handle Y the said piston is caused to descend and bears through the medium of a rod on the valve S which is also held in a closed position by a spring. The valve S descends and the compressed 20 air passes from the compartment α into the compartment α' and from here into the general duct through the tubular extension T' thus increasing the pressure and thereby 25 the height of the mercury level in A and consequently the intensity of the current. When the pressure is no longer exerted on the handle the valves S and S'' are closed by their springs and the pressure and consequently the height of the mercury column 30 as well as the intensity of the current remain the same.

If it is desired to reduce the pressure and consequently the intensity of the current the inverse motion is performed; the handle 35 is raised by means of the same finger whereby the rod H is raised the horizontally bent part H' of which bears on a rod I so as to raise the valve S'. The compressed air escape from the chamber X' through the 40 passage P', the pressure is reduced in the duct and consequently the intensity of the current.

Fig. 2 shows a modified form of the apparatus based on the same principle, the 45 resistance R being wound around a bell B and dipping with it into the mercury. The variations of the height of the level of mercury in the receptacle A are obtained by the variation of the pressure produced in the 50 bell B. The current flows between a conductor V' which is in contact with the mercury, and the end F of the resistance. As to the working of this modified form it is exactly the same as that of the apparatus 55 shown by Fig. 1. It is needless to say that many combinations based on the same principle may be devised. Various means may also be employed for varying the level of the mercury; the pressure of water may for 60 instance be employed or any other similar means, the result would be the same. It would equally be possible to employ another conducting liquid in the place of the mercury.

65 The rheostat described above, owing to

its great sensitiveness and the possibility of being controlled from a distance is very suitable for graduating the temperature in hot air apparatuses where the air is heated means of a resistance which is more or less 70 heated by the passage of a current.

Having now fully described my said invention, what I claim and desire to secure by Letters Patent, is:

1. In a rheostat of the kind described the 75 combination of two communicating vessels, a conducting liquid in said vessels, a resistance coil adapted to coöperate with said conducting liquid, a pressure fluid adapted to exert pressure on the liquid contained in 80 one of said vessels and an indicator receiving the same pressure as the said liquid and adapted to show this pressure, substantially as and for the purpose set forth.

2. A rheostat including spaced intercommunicating vessels, a conducting liquid in each, circuit terminals in one vessel, one of said terminals being at all times in contact with the liquid therein, the other terminal including resistance to be varied as the 90 depth of liquid varies, pressure means for directly varying the depth of the liquid in said other vessel to reversely vary the depth in the first named vessel, and means remote from said vessels for controlling the pressure 95 means.

3. A rheostat including spaced intercommunicating vessels, a conducting liquid in each, circuit terminals in one vessel, one of said terminals being at all times in contact 100 with the liquid therein, the other terminal including resistance to be varied as the depth of liquid varies, pressure means for directly varying the depth of the liquid in said other vessels to reversely vary the depth in the 105 first named vessel, means remote from said vessels for controlling the pressure means, and an indicator to indicate the depth of liquid in the first named vessel.

4. A rheostat including spaced intercommunicating vessels, a conducting liquid in each, circuit terminals in one vessel, one of said terminals being at all times in contact with the liquid therein, the other terminal including resistance to be varied as the 110 depth of liquid varies, pressure means for directly varying the depth of the liquid in said other vessel to reversely vary the depth in the first named vessel, means remote from said vessels for controlling the pressure 115 means, and an indicator open to the pressure means and adapted to indicate the depth of the liquid in the first named vessel.

5. A rheostat including spaced intercommunicating vessels, a conducting liquid in each, circuit terminals in one vessel, one of said terminals being at all times in contact with the liquid therein, the other terminal including resistance to be varied as the 120 depth of liquid varies, pressure means for 125 directly varying the depth of the liquid in said other vessel to reversely vary the depth in the first named vessel, means remote from said vessels for controlling the pressure means, and an indicator open to the pressure means and adapted to indicate the depth of the liquid in the first named vessel.

6. A rheostat including spaced intercommunicating vessels, a conducting liquid in each, circuit terminals in one vessel, one of said terminals being at all times in contact with the liquid therein, the other terminal including resistance to be varied as the 130 depth of liquid varies, pressure means for

directly varying the depth of the liquid in
said other vessel to reversely vary the depth
in the first named vessel, means remote from
said vessels for controlling the pressure
5 means, and an indicator to show the depth
of liquid in the first named vessel, said in-
dicator comprising an open vessel contain-
ing liquid, and an interior bell operable in

10
said open vessel and itself open to the pres-
sure means.

In testimony whereof I have hereunto set
my hand in presence of two witnesses.

LUCIEN CHARLES EILERTSEN.
